Primary Examiner—Louis S. Zarfas*Assistant Examiner*—Gregory Andoll*Attorney, Agent, or Firm*—C. Douglas McDonald, Jr. & Associates, P.A.[57] **CLAIM**

The ornamental design for a disk-holding insert for a storage case for a compact disk, as shown.

DESCRIPTION

FIG. 1 is an upper front perspective view of the disk holding insert of this invention;

FIG. 2 is a front plan view thereof;

FIG. 3 is a rear plan view thereof;

FIG. 4 is a left elevational view thereof;

FIG. 5 is a right elevational view thereof;

FIG. 6 is an upper elevational view thereof; and,

FIG. 7 is a lower elevational view thereof.
